(57) **CLAIM**

The ornamental design for a tub for bathing, as shown and described.

DESCRIPTION

In a preferred embodiment, the nature of this product is as a plumbing fixture primarily useful for washing the body of humans.

FIG. 1 is a right, top, front perspective view of a tub for bathing embodying our new design;

FIG. 2 is a top plan view thereof;

FIG. 3 is a front elevational view thereof, the rear elevational view being a mirror image of the front elevational view shown;

FIG. 4 is a left side elevational view thereof;

FIG. 5 is a right side elevational view thereof;

FIG. 6 is a cross-sectional view thereof taken along line 6—6 of FIG. 2; and,

FIG. 7 is a bottom plan view thereof.

The broken line representations of holes in FIGS. 2-4 and 7, and of a control mounting in FIGS. 1-6, are for the purpose of illustration only, and form no part of the claimed design.
